UNITED STATES PATENT OFFICE.

EDWARD F. THORNTON, OF OREANA, IDAHO.

FIGURE TOY.

Application filed January 10, 1921. Serial No. 436,230.

To all whom it may concern:

Be it known that I, EDWARD F. THORNTON, a citizen of the United States, residing at Oreana, in the county of Owyhee and State 5 of Idaho, have invented new and useful Improvements in Figure Toys, of which the following is a specification.

This invention relates to an improvement in toys, and has particular reference to a toy 10 figure adapted to imitate a person in the act of sawing.

One object of this invention is to provide a toy figure of the character described, which has associated therewith a novel arrangement of parts controlled by a weight element 15 adapted to be oscillated whereby a rocking or swaying motion is imparted to the toy figure.

A further object of this invention is to 20 provide a figure toy of the above mentioned character, which is simple in construction, inexpensive to manufacture, ornamental in appearance, and compact in the arrangement of its parts.

25 Other objects and advantages of the invention will be apparent during the course of the following description:—

In the accompanying drawings forming a 30 part of this specification, and in which like numerals are employed to designate like parts throughout the same,

The figure shown is a side elevation of the toy mounted on a support.

In the accompanying drawings, wherein 35 for the purpose of illustration is shown a preferred embodiment of my invention, the numeral 5 designates a suitable support, preferably the edge of a table, on which is positioned a toy figure. This figure comprises a body portion 6, arms 7, and legs 8 40 which have pivoted thereto feet portions 9 adapted to rest upon the support 5.

The arms 7 embrace a handle 10 of an element 11, which element represents a saw and 45 has provided on its inner edge teeth 11'. When the figure is placed on the support 5, the teeth adjacent the lower extremity of the saw element receive therebetween the lower edge of the support. In normal position the 50 saw element 11 and the body portion of the figure are parallel and the arms 7 are rigidly connected to the handle portion 10 of the saw element 11. In order that a positive connection may be made between the body 6 and the saw element 11, I have shown a cord 12 connecting the two elements.

Suspended from and suitably attached to the saw at a point 12', is a depending member 13, preferably a cord, which has provided on its lower end a weight element 14. 60 This weight element is preferably made in the shape of a round ball, either of metal or rubber, and is the medium through which the swaying action of the figure is started and continued.

65 It will be noted that the point of connection of the upper end of the cord to the saw element is made at a point below the plane of the support.

The operation of the toy is as follows:— 70

The weight element 14, acting as a pendulum, will cause the figure to rock back and forth. The combination formed by the arms of the figure and the handle of the saw, together with the small cord 12, serve to hold 75 the figure upon the support. It will be observed that the teeth of the saw receive therebetween the lower edge of the table and thus likewise assist in holding the figure upon the support. When the weight element is oscillated, the body of the figure being pivoted on the feet portion, will rock thereon and thus 80 imitate a person in the act of sawing.

It is to be understood that the form of my invention, herewith shown and described, 85 is to be taken as a preferred example of the same, and that various changes in the shape, size and arrangement of parts may be resorted to without departing from the spirit of the invention, or the scope of the sub- 90 joined claims.

Having thus described my invention, I 95 claim:—

1. In a device of the character described, the combination with a support, of a toy figure positioned on said support, said figure including a body portion, arms made integral therewith and pivoted feet portions, a serrated element secured to the arms of said figure and resting in a plane parallel with 100 the body portion of said figure, and a weight element suspended from said serrated element and adapted to be oscillated whereby a rocking movement is imparted to the pivoted portion of said figure.

105 2. In a device of the character described, the combination with a support, of a toy figure positioned on said support, said figure including a body portion, arms made integral therewith and pivoted feet portions, a 110 serrated element simulating a saw and secured to the arms of said figure and lying

2
in a plane parallel with the body portion of said figure and contacting with said support, a cord connecting said body to said serrated element, a cord of greater length than the 5 first mentioned cord depending from the lower extremity of said serrated element and connected thereto at a point below the plane of the support, and a weight element secured

to the end of said last mentioned cord and adapted to be oscillated, whereby a rocking 10 movement is imparted to the pivoted portion of said figure.

In testimony whereof I have affixed my signature.

EDWARD F. THORNTON.
